Attorney

UNITED STATES PATENT OFFICE.

JAMES G. SMITH, OF COVINGTON, KENTUCKY, ASSIGNOR TO IDEAL JOURNAL LUBRICATOR COMPANY, OF CINCINNATI, OHIO.

JOURNAL-LUBRICATOR.

SPECIFICATION forming part of Letters Patent No. 728,777, dated May 19, 1903.

Application filed July 28, 1902. Serial No. 117,375. (No model.)

To all whom it may concern:

Be it known that I, JAMES G. SMITH, a citizen of the United States, residing at Covington, in the county of Kenton and State of Kentucky, have invented certain new and useful Improvements in Journal-Lubricators; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in journal-lubricating boxes; and the object of the invention is to generally improve upon the type of lubricating boxes upon which I have secured Letters Patent No. 634,860, of October 10, 1899, and No. 647,886, and in carrying out the present invention it is my purpose to provide an imperforate oil-cellar which is yieldingly mounted within a boxing and provided with a suitable block which is supported transversely within the oil-cellar by means of integral lugs projecting upward from the bottom of the cellar and adapted to hold a block, preferably of asbestos or other suitable material, in an upright position for the purpose of preventing the axle from coming in contact with the walls of the cellar and also serving for the purpose of retaining the absorbent waste on either side of said block, thus causing the same to effectually distribute the oil continuously by capillary attraction over a large area of the circumference of the axle, thus at all times preventing the heating of the box under highest speed imparted to the axle.

The invention consists, further, in various details of construction and in arrangements and combinations of parts, which will be hereinafter fully described and then specifically defined in the appended claim.

My invention is illustrated in the accompanying drawings, in which—

Figure 1 is a sectional view taken on line 11 of Fig. 3. Fig. 2 is a longitudinal view through the box, showing the axle in eleva-

tion. Fig. 3 is a perspective view of the journal-box.

Reference now being had to the details of the drawings by letter, A designates an oil and waste receptacle which has imperforate walls, in which detail it differentiates from the constructions shown in my former patents, in which apertures are formed to receive wicks for the purpose of feeding oil by capillary attraction from the oil-cellar beneath through into the tray, and which features are dispensed with in the present invention. Said oil-receptacle is mounted upon springs C, preferably one adjacent to each corner of the oil-cellar, and posts B rise from the corners of the rectangular frame B', which rests in the boxing B². Said posts B have a play in the guideways G, which comprise recesses with closed tops, which are cast integral with the oil-receptacle, a perspective view of one of these projections in which the recesses are formed being clearly shown in Fig. 3 of the drawings. The springs before referred to bear between said frame B' and the lower face of the oil-receptacle about the margins of the recesses therein and serve to hold the said receptacle yieldingly against the axle D.

Rising from and integral with the bottom of the oil-receptacle are two rows of lugs, (designated by letters F F in the drawings.) Said lugs are arranged, as shown in Fig. 3 of the drawings, with spaces intervening between the same, and their upper edges are in a plane slightly below the cut-away portions H in the opposite edges of the oil-receptacle. A block of any suitable material, preferably of asbestos, (designated by letter E in Fig. 1 of the drawings,) is placed between said vertically-projecting lugs and is held securely in place thereby.

It will be observed in Fig. 1 of the drawings that the upper edge of said block projects above the cut-away margins (designated by letter H) of the oil-receptacle, and one of the purposes of said block is to prevent the axle coming in contact with the cut-away portions H of said receptacle. Another and an essential feature of the block is for the purpose of preventing the waste (designated in the drawings by letter K) from being rolled

in the tray by the axle, and thereby holding the waste stationary and against a large portion of the under surface of the axle to evenly distribute the oil to the surface thereof and 5 prevent heating of the box.

A great deal of trouble has been experienced in actual practice in satisfactorily lubricating the axle by reason of the waste or other absorbent liquid oil-feeding material 10 being drawn away from a portion of the circumference of the axle which turns within or adjacent to the oil-receptacle; but by the provision of the block it has been demonstrated by actual experimenting that the waste is held 15 so as to oil thoroughly the portions of the axle on either side of the block. In practice it has been demonstrated that an axle of an engine which has been equipped with my improved lubricating-box upon one end thereof will not 20 cause heating of the box, whereas with other types of lubricating-boxes on the other end of the same shaft trouble is frequently met with by the heating of the boxes due to the insufficient feeding of the lubricant, thus 25 thoroughly demonstrating the practicability of the improvements which I seek to cover in the present application over the constructions shown in my former patents, which contem-

plate the feeding of the oil through wicks by capillary attraction and which features I dispense with entirely in the present invention. 30

Having thus fully described my invention, what I claim as new, and desire to secure by Letters Patent, is—

A journal-lubricating box comprising in 35 combination with a casing, a rack positioned therein, posts rising from said rack, an oil-receptacle having bosses rising from the bottom thereof said bosses having imperforate tops, and in which bosses said posts are 40 guided, the opposite side walls of said receptacle being cut away, two rows of projections F, spaced apart, and rising from the bottom of the receptacle, a bar seated between said projections and extending above the marginal 45 edges of said cut-away walls, and designed to hold said receptacle from contact with said axle, and a waste packing in the receptacle and adapted to wipe against a rotating axle, as set forth.

In testimony whereof I hereunto affix my signature in presence of two witnesses.

JAMES G. SMITH.
